UNITED STATES PATENT OFFICE.

SVEN LUNDBLAD, OF SEWARD, TERRITORY OF ALASKA.

COMBINATION-BED.

1,211,196.

Specification of Letters Patent. Patented Jan. 2, 1917.

Application filed May 22, 1916. Serial No. 99,211.

To all whom it may concern:

Be it known that I, SVEN LUNDBLAD, a citizen of the United States, residing at Seward city, Territory of Alaska, have invented a new and useful Combination-Bed, of which the following is a specification.

The combination bed, made principally of wood or iron and canvas, is meant to be used in camps and on the trails as a handy sleeping accommodation.

The combination consists of bedstead, mattress, bedcover, pillow-cover, and sleeping-bag, all in one. None of these parts can be described separately.

Figure 1 of the drawings is a top view of the bed or sleeping-bag mounted on the bedstead. Fig. 2 is a side-view of the bed illustrating principally the four sets of cross-pieces, used as legs, which, when in place, have their bearings on the ground at all times, thus dividing the stretch sideways and lengthwise, when a burden that spreads the legs is placed on top of the canvas. Fig. 3 is a cross-section of the mounted combination or the combination cut in two, showing parts of bedstead, mattress, bed-cover, pillow-cover, the two smaller cross-pieces, used as legs, in part, and one of the two bigger cross-pieces, also used as legs, the first mentioned cross-pieces stretching against the side poles, the latter against the end-poles. Fig. 4 is a top-view showing in dotted lines where the cross-pieces or legs fit in in the side-poles and in the end-poles respectively, the cross-pieces folded together, and other parts. Fig. 5 is an end view of the mounted bed or sleeping bag, showing principally the adjustment of one of the smaller crosspieces or legs into one of the two side-poles.

The bedstead is composed of two smaller cross-pieces, 6, and two bigger cross-pieces, 7, all used as legs, two side-poles, 8, and two end-poles, 9, each numeral to be more fully explained as the specification proceeds and touches parts connected with them.

The mattress is composed of a canvas-tick, 10, filled with stuffing, 11, any kind of which is handily found, such as spruce-boughs, leaves or grass, whenever a stop is made or the bed is to be used.

The bedcover is a flap of canvas, 12, the width of the bed, that extends from the foot of the bed to the head and which together with the mattress and laceable extensions of the mattress-tick, called retainers,

13, forms a sleeping-bag of superior worth. It can be regulated tight or loose according to the prevailing temperature by means of a lacing-gear, 14.

The pillow cover, 15, is a flap of canvas, turned over the contents of a pillow as demonstrated below.

The four sets of cross-pieces, each joined together with a bolt, 16, are the legs, the two smaller ones stretching against the side-poles, 8, that run lengthwise between two seams on the canvas, the two bigger ones against the end poles, 9, which are inserted in sleeves, sewed on crosswise on the bottom-sheet of the canvas. All four cross-pieces touch the ground, used as they are as legs, none as stretchers only. The relative length of these legs is regulated so as to give a simultaneous stretch sidewise and lengthwise on the canvas when a weight is placed on the bed. A perfect balance is effected through this arrangement, as the legs take position according to the pressure from above, while the heft on the long side-poles, 80 by means of the tension lengthwise on the canvas, is considerably lessened to avoid a breakage. The V-shaped cuts, 17, in the upper ends of the smaller crosspieces fit in incisions, 18, on the ends of the side-poles. 85 The V-shaped cuts, 19, on the upper ends of the bigger crosspieces fit in incisions, 20, on the ends of the end-poles.

The canvas is doubled, the upper and lower sheets being even along the sides. 90 Two sets of seams run lengthwise to make room for the side poles and determine the width of the bed. The canvas continues on the outer side of the side-poles, where it is turned up in order to form the retainers, 13, 95 for the bedding. These retainers are held in place by laces, 14, running zig-zag through loopholes from one retainer to the other, starting at the foot end of the bed. This makes it handy for the occupant of the bed to tie the laces across the body to suit. At the foot end the canvas is open to receive the filling of the tick, the upper sheet of which is cut off, while the lower

extends and is folded over on top of the bedding, running under the laces, thus, when the laces are applied, forming a tight cover over the bedding and establishing together with the retainers a complete sleeping bag with mattress-bottom. At 110 the head end the canvas or the tick is closed, the upper canvas being cut off, while the

lower extends to form a pillow-cover under which anything, as, for instance, the clothes you remove when going to bed, is placed, if no other filling is handy. When the pillow is formed the pillow flap is buttoned or tied to the upper sheet of the canvas or simply laid over the filling. The facility with which the tightness of the sleeping bag is regulated makes it possible to dispose with a whole lot of the usual bed-clothes. If very cold the laces may be tied over the head.

I claim:

1. A bed comprising in combination, a flexible bed bottom, a long flap secured to one end of the bed bottom and adapted to overlie the bed-bottom to form a mattress by inclosing a filler between it and the bed bottom, and a short flap secured to the same end of the bed bottom and adapted to be folded over said long flap to form a pillow by including a filler between itself and said long flap.

2. A sleeping bag comprising a flexible bottom, a downwardly extending flap fastened to the bottom near the head end adapted to overlie a filling and thereby form a mattress, another flap at the head

end adapted to overlie a filling and thereby form a pillow, and a third flap at the foot end adapted to be laid back over said mattress and pillow.

3. A sleeping bag comprising a flexible bottom, a downwardly extending flap fastened to the bottom near the head end adapted to overlie a filling and thereby form a mattress, another flap at the head end adapted to overlie a filling and thereby form a pillow, a third flap at the foot end adapted to be laid back over said mattress and pillow, and side flaps secured to the bottom along the sides and drawn together in the middle of the bed by a lacing.

4. A camp bed comprising a flexible bottom with a hem at each side forming tubes, poles extending through said tubes, flaps attached to the bottom near the ends forming similar tubes, pairs of crossed legs at the ends, pivotally connected, supporting the longitudinal poles, and pairs of crossed legs at the sides, pivotally connected, supporting the transverse poles.

Signed at Seward city, Territory of Alaska, this 2nd day of Jan. 1916.

S. LUNDBLAD.
